UNITED STATES PATENT OFFICE.

FOREST G. GAUNTT, OF FORT WAYNE, INDIANA, ASSIGNOR TO W. J. SAVAGE COMPANY,
OF KNOXVILLE, TENNESSEE, A CORPORATION OF TENNESSEE.

BAG-CLEANER.

1,268,450.

Specification of Letters Patent. Patented June 4, 1918.

Application filed October 20, 1915. Serial No. 56,876.

To all whom it may concern:

Be it known that I, FOREST G. GAUNTT, a citizen of the United States of America, residing at Fort Wayne, Allen county, Indiana, have invented new and useful Bag-Cleaners, of which the following is a specification.

This invention relates to apparatus for recovering fine particles of material from containers.

This invention has utility when embodied in devices for the separation and collection of fine particles of material, as flour, cement, etc., from bags or containers, as well as removing the fines from mill sweepings, say in cereal mills, and similar purposes, thereby enabling reclaiming of material for feed, or use.

Referring to the drawings:

20 Figure 1 is a front elevation of an embodiment of the invention, with the receiving chamber doors open;

25 Fig. 2 is a fragmentary view showing the opposite direction of rotation with discharge device gate closed, instead of open as in the broken away portion shown in Fig. 1;

30 Fig. 3 is a fragmentary view of the housing from the opposite end of the drum from the showing in Fig. 2 with the gate shown as away from the collection discharge or dust chamber;

35 Fig. 4 is a side elevation from the right of the showing in Fig. 1, with the drum rotated about 180° and portions broken away;

40 Fig. 5 is a view similar to Fig. 4, with the drive shifted for reverse travel, and more portions broken away;

45 Fig. 6 is a detail of the drive control in stopping position; Fig. 7 is a fragmentary view on an enlarged scale of the discharge pocket in opening position as shown in Fig. 1; Fig. 8 is a view from the left of Fig. 7 looking at the open pocket; Fig. 9 is a fragmentary view on an enlarged scale of the closed pocket of Fig. 2; Fig. 10 is a side elevation, still further enlarged, from the opposite side of the showing in Fig. 9; and Fig. 11 is a perspective view, with parts broken away, of the closed pocket.

50 The brackets 1 carry the idler sustaining rollers 2, while similar brackets 3 carry the driving shaft 4 which has fast thereon the actuating sustaining rollers 5. The rollers 2, 5, travel on the tracks 6 of the movable

drum or rotary housing having the outer 55 shell 7 mounted on the heads 8, 9. Axially disposed as to the head 9 is the opening 10 which may be closed by the pair of doors 11. This is the entrance or charging opening for the receiving chamber into which used 60 sacks, bags, or sweepings may be introduced, and then the doors 11 closed for confining the fine material or dust therein.

The receiving chamber comprises an annular wall and an annular series of slats 12 65 mounted on the heads 8, 9, parallel with the axis of the drum. Extending about the slats 12, to leave the slats 12 inside the receiving chamber as beaters, is the perforate 70 wall portion or mesh work 13. For supplementing the beating action of the slats 12, inwardly angularly extending arms 14 rigid with the housing are provided, effective in working the falling material or objects to the center of the drum. This meshwork 13 75 is spaced from the outer shell 7 to form the collection chamber to which delivery of the separated matter is made by the agitation in the receiving chamber to pass through the perforate wall portion thereof. 80

The rotary collection chamber has therein a chute 15 provided with the wing 16 to conduct accumulated material into the hood 18 through the opening 17 in the drum shell 7. This hood 18 or discharge device is normally closed by the gate 19, held shut by the spring 20.

In operation, the device is idle when the handle 21 is in the position shown in Fig. 6. The cam slot 22 has thrust the pin 23, 90 and with it the collar 24 away from the collar 25, so that the rod 26 fast with the collar 24 is shifted through the collar 25 away from the lever 21. The rod 27 is made fast to the collar 25 and carries the belt shifting 95 fingers 28, which in this idle position hold the belt 29 on the loose pulley 30. The rod 27 is fast with the collar 25 and slidable through the collar 24. The rod 26 carries the belt shifting fingers 31 for shifting the 100 belt 32, now held for driving the loose pulley 33 in an opposite direction to the driving of the loose pulley 30 by the belt 29. Between these spaced loose pulleys 30, 33, is the pulley 34 fast on the shaft 4.

The intermediate portion 35 of the shaft 4 carries the traveling nut 36 embracing the rods 26, 27. Shifting of the hand lever 21

from the position shown in Fig. 6 to the position shown in Fig. 4, brings the belt 32 from pulley 33 to the fast pulley 34, say for rotation in the direction of the arrow. The traveling nut 36 will move toward the spring 37, compress this spring a little, and then through the collar 38 fast on the rod 27, start shifting of the belts from the pulleys 30, 34, to the pulleys 34, 33. This double shifting 10 of the belts is effected in that the pull of collar 38 on the rod 27 acts against the collar 25 carrying the lever 21 and pulls the collar 24 to bring the rod 26 along with the rod 27, thus moving the fingers 28, 31 simultaneously. This starting in the shifting has its completion insured through the link 39 from the collar 25 to the weighted arm 40, for this arm is carried past its center and the weight thereof finishes the throwing over of the 20 belts. The power of this throw over may be adjusted by varying the distance of the weight out on the arm 40.

This reversal of rotation of the shaft 4 due to shifting the belts changes the direction 25 of driving rotation of the drum and starts the nut 36 away from the spring 37 toward the spring 41 on the rod 26. The alternating rotary driving mechanism is in the position shown in Fig. 5, and as the nut 30 36 reaches the spring 41 and compresses it, the collar 42 effects shifting of the rods 27, 26, as assisted by the weighted arm 40, to bring the belts 29, 32, back to the pulleys 30, 34, the driving rollers 5 having effected, according 35 to the pitch of the threaded portion 35, and the effective length thereof, some determined number of rotations, as seven, of the drum or housing. These operations are automatically repeated until the machine 40 is thrown to idle position. There is thus a thorough agitation of the material in the receiving chamber, and as the material works out into the collection chamber, in one direction of rotation, the sifted matter accumulating 45 in the chute 15. But in this direction of rotation shown in Fig. 2, and in the position shown in Fig. 3, having the drums rotated some 300° from the showing in Fig. 2, there is no discharge from the 50 chute 15 or its delivery hood 18, because the gate 19 is maintained closed by the spring 20. However in the direction of rotation shown in Fig. 1, the pin 43 on the gate 19 is engaged by the arm 44 pivoted on the same hinge as the gate 19 and has at its free end, the roller 45 coating with the track 46 in the dust chamber 47. This movement of the 55 arm 44 in an arc away from the pocket or hood 18, opens the gate 19 so material may drop in the receptacle or drawer 48. Openings 49, 50, in the chamber 47, permit the hood 18 to clear in its travels. In the downward travel of the hood 18 through the dust chamber 47, the arm 44 with the roller 45 60 coating with the track 46 is moved away 65

from the gate 19, and with the gate thus undisturbed and closed no discharge occurs. With the gate thus closed in this direction of travel, the hood cannot act as a scoop to disturb fine particles of dust by scattering 70 about the machine or allow it to blow back from the collection chamber into the receiving chamber. Away from the track 46, the spring 20 is sufficiently strong to keep the arm 44 from opening the gate 19. Accordingly the track 46 has no action upon the gate 19 in counter-clockwise rotation of the drum but in clockwise rotation of the drum this track 46 is effective through engaging the roller 45 on the loose arm 44 causing the 80 arm 45 to strike the pin 43 on the gate 19 to open the gate against the retracting or closing action of the spring 20.

In the handling of say flour sacks, they may be dumped into the machine in quantity 85 of a hundred or more, even without turning the sacks wrong side out, the machine started and left for 10 to 30 minutes. The sacks may then be removed thoroughly cleaned, the flour reclaimed for mixing in feed, and all in a cleanly manner without damage to the sacks. The number of rotations of the drum or housing may be varied by re-setting the collars 38, 42, respectively on the rods 27, 26 as adjusted by the set screws 51. 95

What is claimed and it is desired to secure by Letters Patent is:

1. A movable housing embodying a material receiving chamber having inwardly projecting arms, a collection chamber supplied from said receiving chamber, and a discharge device for the collection chamber including a pocket carried by the chamber and means for opening said pocket. 100

2. A movable housing comprising receiving and collection chambers, and a discharge device for removing material from the collection chamber including a pocket having a closure, and a guide for opening said pocket. 105

3. A movable housing comprising receiving and collection chambers, and an intermittently operable discharge device therefor including a guide coating in one direction of travel for removing material from the discharge device. 115

4. A rotatable housing comprising receiving and collection chambers, a collection chamber chute, and a discharge device for the chute including a pocket, a hinged door 120 for the pocket, and a guide for opening the door.

5. A rotatable housing embodying a perforate material receiving chamber having an end provided with a charging opening, 125 means for closing the opening during rotation of the housing, a collection chamber in communication with the receiving chamber through the perforate portion of the receiving chamber, and a discharge device for re- 130

moving material from the collection chamber including a pocket and a valve for opening the pocket.

6. An alternating rotary housing embodying a material receiving chamber, a rotary collection chamber radially exterior of the receiving chamber supplied from said receiving chamber, said collection chamber having a chute, and a discharge device rotatable with the collection chamber and provided with a pocket adjacent said chute and radially exterior of the collection chamber.

7. A movable housing embodying a material receiving chamber having beaters therein, a collection chamber supplied from said receiving chamber, and a discharge device for the collection chamber including a valve controlled device movable with the housing, said housing being peripherally imperforate except for the valve controlled device.

8. A movable imperforate housing embodying a material receiving chamber having parallel slats, a collection chamber supplied from said receiving chamber, and a discharge device for the collection chamber including an automatic valve device movable with the housing and providing an opening through the otherwise imperforate housing.

9. An alternating rotary imperforate housing embodying a material receiving chamber therein comprising an annular series of parallel slats and mesh work thereover, a collection chamber supplied through said mesh work from the receiving chamber, and a discharge device for the collection chamber including a pocket rotatable with the housing, and a stationary guide for opening the pocket.

In witness whereof I affix my signature.
FOREST G. GAUNTT.
